UNITED STATES PATENT OFFICE

141,390

DESIGN FOR A PUTTING GAME DEVICE

Lloyd R. Welsh, Haskins, Ohio

Application February 16, 1945, Serial No. 117,998

Term of patent 14 years

(Cl. D34—5)

To all whom it may concern:

Be it known that I, Lloyd R. Welsh, a citizen of the United States and resident of Haskins, in the county of Wood and State of Ohio, have invented a new, original, and ornamental Design for a Putting Game Device, of which the following is a specification, reference being had to the accompanying drawing, forming a part thereof.

In the drawing, Figs. 1 and 2 are front and rear perspective views, respectively, of a putting game device showing my new design, and Figs. 3 and 4 are side and top plan views thereof, respectively.

I claim:

The ornamental design for a putting game device, substantially as shown.

LLOYD R. WELSH.
